FIG. 2
INVENTOR.

Augustus Beals
by Alex. P. Browne, attorney

UNITED STATES PATENT OFFICE.

AUGUSTUS BEALS, OF NORTH WEYMOUTH, MASSACHUSETTS.

HAMMOCK.

SPECIFICATION forming part of Letters Patent No. 403,320, dated May 14, 1889.

Application filed May 3, 1888. Serial No. 272,628. (No model.)

To all whom it may concern:

Be it known that I, AUGUSTUS BEALS, of North Weymouth, in the county of Norfolk and State of Massachusetts, a citizen of the 5 United States, have invented certain new and useful Improvements in Hammocks, of which the following is a specification.

I have already made application, Serial No. 263,814, filed February 13, 1888, for a patent 10 for a hammock in which a portion of the end of the fabric is folded over upon itself and is woven around a stay cord or wire of the desired stiffness and thickness for the purpose, so that one-half of the warp-threads loop 15 around the cord or rod, and a series of loops is formed across the end of the hammock, one end of each loop passing around the cord, the other end of the loop being left out a sufficient distance for the ready attachment of the 20 supporting-cords, or, if desired, to such a distance that the loop itself may be used for supporting the hammock.

My present invention relates to an improved construction of the hammock, whereby 25 the supporting-loops and stay-cord are united in a much neater and better way than has heretofore been practiced.

In the drawings, Figure 1 is a plan view, and Fig. 2 a sectional view on an enlarged 30 scale, of a portion of the end of a hammock embodying my invention. Figs. 3, 4, 5, and 6 are detail views, as will hereinafter be more fully explained, further illustrating the construction of the hammock.

35 Referring to the drawings, A represents the hammock-body, composed of woven yarn, which I prefer, although any suitable reticulated or woven material may be used. The threads shown at Fig. 1 as running up and 40 down are the warp-threads *a*, and those running across are the filling-threads *b*.

B represents the stay-cord, lying within the 45 folded end or hem of the hammock, as shown in Fig. 2. Bights or loops of the supporting or loop cord C surround the stay-cord B, and are shown as gathered together and knotted to the suspension-cord D in a well-known manner.

In the finished structure I prefer to run a 50 line of machine-stitching (indicated at *c*) through the stay-cord B, thus confining the

loops around the stay-cord and preventing their accidental displacement.

I will now describe the method which I prefer to follow in making my improved construction, as I believe that this will illustrate more clearly the construction itself.

In carrying out my invention, I first cause bights or loops of the loop-cord to pass through meshes of the hammock fabric at a distance 60 from the end approximately equal to the depth of the hem to be turned and at intervals across the hammock, the length of the intervals being governed by the number and location of the loops desired. The work now is in the 65 condition shown in plan at Fig. 3 and in end elevation at Fig. 4. I next carry a stiffening-wire or stay-cord, B, across the hammock-body and through the series of loops, as shown at Fig. 5, then draw each loop out onto the upper 70 or outer side of the fabric, the loops now being drawn tight around the stay-cord, as shown in Fig. 6. The end or hem of the hammock may now be folded over upon the hammock, so that all the warp-threads envelop the rod, as 75 shown in Figs. 1 and 2, and secured—as, for example, by one or more rows of stitches, *e* *e*, and a similar row, *c*, taken, if desired, through and through the stay-cord, when a 80 cord is used, to keep the loops of the loop-cord in place. The outer ends of the loops may be attached to the supporting-cords in any desired manner, as shown in Fig. 1, or if the loops are of sufficient length they may themselves be used as supports. 85

By the construction herein described the hammock is not only more securely attached, but a very neat, simple, and effective finish is given to it.

I do not broadly claim the hammock fabric, 90 stay-cord, and supporting-cord either alone or in combination, for all of them are shown in my application above referred to. In that application, however, the supporting-cord is shown as knotted or tied around the stay-cord, 95 and the row of knots thus produced is objectionable in the finished hammock for various reasons. By my present improvement, as will be perceived, I do away with all knotting of the supporting-cord around the stay-cord, 100 and thus materially improve the finished article.

I am also aware that hammocks have been heretofore constructed—as, for example, those shown in United States Letters Patent No. 217,964—in which a netted or woven hammock-body has been provided with a flexible eyeleted border and the supporting-cords have been passed through the eyelets in this border. Such a construction I consider undesirable, in view of the expense of forming and applying this eyeleted border. By my present improvement I do away with such a border and attach my supporting-cords, as above stated, directly to the woven hammock-body.

I claim—

15 In a hammock, the combination of a woven

fabric, a stay cord or rod hemmed in place by the entire warp-threads of the fabric, and a supporting-cord looped into the fabric and around the stay rod or cord, its loops passing through the fabric, so as to form bights around the rod or cord, and extending outwardly to a suspension-rope, substantially as described.

In testimony whereof I have hereunto subscribed my name this 28th day of April, A.D. 1888.

AUGUSTUS BEALS.
